UNITED STATES PATENT OFFICE.

ALFRED COTTON, OF ST. LOUIS, MISSOURI, ASSIGNOR TO HEINE BOILER COMPANY, OF ST. LOUIS, MISSOURI, A CORPORATION OF MISSOURI.

WATER-TUBE BOILER.

Application filed December 8, 1921. Serial No. 520,871.

To all whom it may concern:

Be it known that I, ALFRED COTTON, a citizen of the United States, residing at St. Louis, Missouri, have invented a certain 5 new and useful Improvement in Water-Tube Boilers, of which the following is a full, clear, and exact description, such as will enable others skilled in the art to which it appertains to make and use the same.

10 This invention relates to water tube boilers of the type that comprise a plurality of banks of upright water tubes connected at their upper ends to transverse steam-and-water drums.

15 It has for its main object to provide a highly efficient three bank boiler of such design that drier steam will be supplied than is possible with boilers of this general type now in use and which can be driven 20 at a high rate without liability of causing the water level in the rear steam-and-water drum to be lowered to such a point as to expose the upper ends of the tubes of the rear bank, and thus cause the expanded 25 joints between the upper ends of said tubes and the rear drum to leak, due to over-heating of said joints.

To this end I have devised a three bank, semi-vertical tube, transverse drum boiler, 30 in which the water tubes at the front side of the first bank which are exposed to radiant heat are connected at their upper ends to the front steam-and-water drum, and the remaining tubes constituting more than half 35 of those in said first bank, and which depend mainly on convected heat, are connected at their upper ends to the middle or second steam-and-water drum of the boiler, said front and middle drums being connected together by water circulators of cross-sectional 40 area approximating to that of those tubes of the first bank, which enter the front drum. In a boiler of the construction above described, the upflow of steam and water into the front drum is considerably less 45 than in conventional boilers of this general type now in use, owing to the fact that only the tubes at the front side of the first bank conduct steam and water into the front drum. As less steam and water flows into the front drum than is the case in boilers of this general type, and as the cross-sectional 50 area of the water circulators approximates to that of the tubes entering the front drum, there is practically no tendency 55 for the water level to rise in the front drum, whereas, in boilers of this general type where the whole of the tubes in the first bank discharge into the front drum and where the cross-sectional area of the water 60 circulators is always less than one-half and often less than one-third of the area of the tubes discharging into the front drum, the water level in the front drum rises very considerably, so that at high loads it reaches to the steam circulators. This raising of the water level in conjunction with discharging the whole of the steam and water from the first bank into the front 65 drum in conventional boilers causes the water in the front drum to be very tumultuous and to throw up a considerable amount of spray which is carried over very readily, owing to the water level rising into close proximity with the steam circulators. The 70 amount of water carried in suspension by the steam in any boiler is dependent upon the area of the "steam disengaging surface", which is that part of the surface of the water where the steam leaves it. The 75 smaller this surface is, the more tumultuous it is, and the more water is carried away with the steam, which is an obvious fact, long and well known to engineers generally. In conventional boilers of this general type 80 wherein the whole of the tubes of the first bank discharge into the front steam-and-water drum, the "disengaging surface" is the surface of the water in the front drum only, since the steam disengaged in the other 85 drums is quite negligible for all practical purposes. In a boiler embodying my invention, wherein a large proportion of the steam and water flowing up the first bank is discharged into the middle drum, the surface of the water in the middle drum is a 90 "disengaging surface" additional to that of the front drum. A further increase in the amount of disengaging surface is caused by avoiding the rise of water level in the 95 front drum which takes place in conventional boilers and which narrows the disengaging surface therein. The amount of disengaging surface in my improved boiler is consequently about three times that of 100 conventional boilers, and the water surface is therefore so much less tumultuous. The result is that drier steam will be supplied, as the water in the front drum is calmer 105 than is usual in boilers of this general type 110

and is not liable to rise to such a level as to be carried over with the steam into the middle drum, and as part of the steam is disengaged from the water in the middle drum, as well as in the front drum, the amount of disengaging surface is very much greater than in conventional boilers. Such a boiler as herein described can be driven at a high rate without causing the water level in the rear drum to drop to such a point as to expose the expanded joints by which the upper ends of the tubes of the rear bank are secured to the rear drum, because the rise of water level in the front drum which causes a corresponding drop of the water level in the rear drum is very slight, as above mentioned. The disturbance of water levels is caused by the steam bubbles rising in the tubes of the first bank inducing an upward flow of water therein, so that any restriction of downward flow from the front drum to the mud drum raises the water level in the front drum and lowers the pressure in the mud drum, and the water level in the rear tube bank and drum falls until this lowered pressure in the mud drum is balanced. Accordingly, where the restrictions to circulation are removed, as in the boiler above described, the disturbance of water levels is reduced to a negligible amount in comparison to the objectionable disturbance of water levels taking place in boilers of conventional design of this general type.

The figure of the drawings is a vertical longitudinal sectional view of a boiler constructed in accordance with my invention.

Referring to the drawings, A, B and C designate the front, middle and rear steam-and-water drums of my improved boiler, D designates a mud drum and E, F and G designate front, middle and rear banks of upright water tubes. The tubes at the front side of the front bank E which are exposed to radiant heat, consisting of the first two or three transverse rows of tubes, have their upper ends connected to the front steam-and-water drum A. The remaining tubes of said front bank, consisting of the tubes which depend mainly on convected heat, have their upper ends connected to the middle steam-and-water drum B. The tubes of the middle bank F which act as down-comers are connected at their upper ends to the middle drum B and the tubes of the third bank or economizer bank G are connected at their upper ends to the rear steam-and-water drum C. Steam circulators 1 and water circulators 2 are provided for connecting the steam-and-water drums together, and the rear drum C is provided with a steam outlet 3 and a feed water inlet 4. The baffling comprises a first baffle 5 arranged transversely of the boiler at the

rear side of the front tube bank E with its lower end terminating at the mud drum D and its upper end spaced away from the middle drum B, and a second transversely-disposed baffle 6 that extends downwardly from the middle drum B at the rear side 70 of the middle bank F and terminates at a point above the mud drum D, thus causing the gases to circulate through the various banks in the manner indicated by the arrows and escape through an outlet 7 at the 75 upper end of the boiler setting.

When the boiler is in operation part of the water that flows upwardly through the tubes of the front bank E enters the front steam-and-water drum A, and the remainder of the water that flows upwardly through said front bank enters the second drum or middle drum B, the water that enters the front drum A escaping from same into the middle drum B, through the water circulators 2 between said drums, which are preferably of such cross-sectional area as to insure a free and rapid escape of the water from the front drum into the middle drum. All of the water that enters the middle drum B flows downwardly through the downcomer tubes constituting the middle bank F to the mud drum D. By constructing the boiler in such a manner that only part of the water which flows upwardly through the front bank enters the front drum A, the resistance to circulation is materially reduced, as a large proportion of the water that flows upwardly through the front bank enters the middle drum B and 100 flows transversely across same to the down-comers F without having to encounter the resistance to flow of any water circulators. Consequently, the water in the front drum will be much calmer than is usual in boilers of this general type, even when the boiler is driven at a high rate, and is not liable to rise to such a level as to be carried over with the steam into the middle drum, thus insuring the production of drier steam 110 in the front drum A of the boiler. Moreover, such a boiler can be driven at a high rate without liability of causing the water level in the rear drum dropping to such an extent as to uncover the expanded joints 115 between the upper ends of the tubes of the rear bank and the rear drum, due to the fact that a large proportion of (or more than half of) the tubes of the front bank are connected to the second steam-and-water 120 drum in such a manner that there is no tendency for the water to accumulate in the front drum, due to restriction of circulation, as frequently occurs in conventional boilers of this general type, wherein all of the water flowing upwardly through the front bank passes through the front drum before entering the middle drum.

Having thus described my invention, what I claim as new and desire to secure by Letters Patent of the United States is:

1. A water tube boiler, comprising at least two elevated transverse steam-and-water drums arranged one in front of the other, a transverse mud drum, a front bank of water tubes combined with said mud drum and said elevated drums in such a manner that the tubes that are subjected mainly to convected heat and which are directly connected at their upper ends to the second elevated drum offer the major cross-sectional area of path to the water which circulates upwardly through said bank and the remainder of the tubes, at the front side of said bank which are exposed to radiant heat and which have their upper ends connected to the front drum offer the minor cross-sectional area of path to said upwardly circulating water, water circulators that connect the front drum with the second drum, downcomer tubes that lead from said second drum to the mud drum, and means for causing the fire gases to flow upwardly over said front bank and downwardly over said downcomer tubes.
2. A water tube boiler provided with a first and a second transverse steam-and-water drum, a transverse mud drum, a front bank of water tubes connected at their lower ends to said mud drum and comprising a relatively few radiant heat tubes whose upper ends are connected to the first drum and a greater number of convected heat tubes whose upper ends are connected to the second drum, water circulators between said first and second drums of approximately the same cross-sectional area as the radiant heat tubes connected to said first drum, downcomer tubes leading from said second drum to the mud drum, and baffles arranged to cause the gases to flow upwardly over said front bank and downwardly over said downcomer tubes.
3. A water tube boiler comprising three elevated transverse steam-and-water drums, a transverse mud drum, a front bank of water tubes comprising a few transverse rows of tubes at the front side of said bank connected at their upper ends to the front steam-and-water drum and a greater number of transverse rows of tubes connected at their upper ends to the middle drum, a middle bank of downcomer tubes connected at their upper ends to said middle drum, a rear bank or economizer bank of tubes connected at their upper ends to the rear drum, steam-and-water circulators between said steam-and-water drums, the lower ends of the tubes of each bank being connected to the mud drum and the water circulators between the front and middle drums being of approximately the same cross-sectional area as the tubes at the front side of the first bank whose upper ends are connected to said front steam-and-water drum, and baffles arranged to cause the gases to flow upwardly over said front bank and downwardly over said middle bank.
4. A water tube boiler, comprising three elevated steam-and-water drums, a mud drum, an economizer bank of tubes that connects the rear drum with the mud drum, a downcomer bank of tubes that connect the middle drum with the mud drum, a front bank of upflow tubes composed of a few transverse rows of tubes at the front side of said front bank which connect the mud drum with the front steam-and-water drum and a greater number of transverse rows of tubes that connect the mud drum with the middle steam-and-water drum, steam and water circulators between said steam-and-water drums, and baffles for causing the gases to flow upwardly over the front bank, downwardly over the downcomer bank and upwardly over the economizer bank.

ALFRED COTTON.
